US0D1009360S

(12) **United States Design Patent** (10) **Patent No.:** **US D1,009,360 S**
Cheng et al. (45) **Date of Patent:** **** Dec. 26, 2023**

(54) **ACCESSORY FOR HAIR STYLING AND HAIR CARE APPARATUS**

(71) Applicant: **Dyson Technology Limited**, Wiltshire (GB)

(72) Inventors: **Howard Shi-How Cheng**, Swindon (GB); **Sze Siang Lim**, Singapore (SG)

(73) Assignee: **Dyson Technology Limited**, Malmesbury (GB)

(**) Term: **15 Years**

(21) Appl. No.: **29/806,215**

(22) Filed: **Sep. 1, 2021**

(30) **Foreign Application Priority Data**

Mar. 2, 2021 (EM) 008448450-0007

(51) **LOC (14) Cl.** **28-03**

(52) **U.S. Cl.**

USPC **D28/17**

(58) **Field of Classification Search**
